ABSTRACT

The ignition circuit of a spark plug of an internal-combustion engine includes a storage condenser in series with a controlled rectifier which is periodically triggered under the control of an engine-driven cam switch by a blocking oscillator comprising a transistor with grounded emitter in series with the primary of a coupling transformer. One secondary winding of that transformer is inserted, together with a pair of diodes, in a charging path for the storage condenser while another secondary winding lies between the emitter of the transistor and its base which is connected through a feedback resistor to the collector thereof and via an R/C network to the gate of the controlled rectifier. During the open phase of the cam-switch cycle, the base is grounded through the last-mentioned secondary winding which is so poled as to intensify a firing pulse capacitively transmitted to the base upon the opening of the switch; at the same time the controlled rectifier is turned on to discharge the previously charged storage condenser through the ignition circuit, whereupon the transistor cuts off and the condenser is recharged by the reversed transformer voltage.

IGNITION CIRCUIT FOR SPARK PLUGS OF INTERNAL-COMBUSTION ENGINE

My present invention relates to a system for intermittently firing a spark-discharge device, such as a spark plug in an internal-combustion engine of an automotive vehicle.

The ignition circuit of an automotive spark plug generally includes a storage condenser which is alternately charged from a direct-current source, such as the vehicular battery, and discharged through a step-up transformer generating the high voltage necessary to break down the spark gap. The timing of the discharge is controlled by a switch operated by the cam shaft of the engine, which in a four-cylinder model may execute about 7,000 revolutions per minute.

It has already been proposed to charge the storage condenser through a coupling transformer in the output circuit of a monostable blocking oscillator periodically tripped by the cam-operated switch whereby the contacts of the latter are traversed by only a small fraction of the charging current and are thus less subjected to wear. In such a system a contactless switching device, such as a controlled rectifier of the silicon type (SCR), may be used to close the discharge circuit of the storage condenser at a predetermined point in the cycle. Prior systems of this kind, however, were relatively cumbersome and expensive.

It is, therefore, the general object of my present invention to provide a simplified ignition system of this character for the firing of automotive spark plugs and related devices.

This object is realized, pursuant to the present invention, by the provision of a three-winding coupling transformer having its primary winding in series with the output electrode (collector) of a transistor forming part of the blocking oscillator; one secondary winding of the transformer is connected between the input electrode (base) and the common electrode (emitter) of the transistor with such a polarity as to intensify both blocking and unblocking potentials applied to that input electrode via a resistive feedback connection, another secondary winding of the same transformer lying in the charging circuit of the storage condenser whose discharge circuit includes a normally open electronic switch (such as a silicon controlled rectifier) with a control circuit extending from the transistor input to close that switch in the presence of an unblocking potential, i.e. when the transistor conducts. Thus, a reversal of the cam-operated switch to bias the transistor into conduction causes a rising current flow through the coupling transformer which regeneratively energizes the transistor input (its base) and is also communicated to the control electrode for the electronic switch (i.e. the SCR gate) to discharge the previously charged storage condenser; as the transistor and/or the core of the coupling transformers saturates, the regenerative feedback diminishes and the transistor begins to cut off, the resulting polarity reversal in the several transformer windings resulting in the flow of charging current into the condenser whose discharge circuit is broken at this point by the reopening of the electronic switch.

The invention will be described in detail hereinafter with reference to the accompanying drawing the sole FIGURE of which diagrammatically illustrates a representative embodiment.

The drawing shows an ignition system for a spark plug 10 of an automotive engine, not further illustrated, which drives a shaft 11 with a cam 12 periodically opening normally closed switch P. A source of direct current 13, such as the battery of a vehicle powered by the engine, generates a positive voltage V_b on a bus bar 14 and has its negative terminal grounded. Bus bar 14 is connected, within a blocking oscillator generally designated Ob, to the collector of an NPN transistor 10 Q1 through the primary winding N_p of a coupling transformer Tr having a core 15 with two further windings thereon, i.e., a feedback winding N_f and a load winding N_L . The relative polarities of the currents flowing through these windings have been conventionally indicated by dots.

Switch P lies between ground and bus bar 14 in series with a leakage resistor R1. The junction of this resistor with switch P is connected to the base of transistor Q1 through a circuit including, in series, a capacitor C1 and three resistors R2, R3 and R4. Two diodes D1 and D2 are shunted across resistors R2 and R3, respectively, with a polarity allowing positive pulses from capacitor C1 to bypass the resistors R2 and R3 in flowing to the base of the transistor Q1 to unblock it. This base is normally maintained at emitter potential (ground) through transformer secondary N_f inserted between ground and the junction of resistors R2 and R3, the same junction being connected to the collector of the transistor by way of a feedback resistor R6. An integrating circuit, consisting of a resistor R5 in parallel with a condenser C3, lies between the base and the emitter of transistor Q1 to shunt voltage transients to ground.

The other transformer secondary N_L is connected in a charging circuit for a storage condenser C4 in series with a pair of diodes D3 and D5. A discharge circuit for condenser C4 includes the primary of a voltage-step-up transformer THT whose secondary feeds the spark plug 10, its primary lying in series with an SCR D4 having its gate connected to the junction of resistors R3 and R4 in the input circuit of transistor Q1 by way of an R/C network consisting of a condenser C2 and a resistor R7 in parallel therewith.

The operation of the system shown in the drawing will now be described.

As the rotating cam 12 opens the main switch P at a predetermined point in its cycle, the previously grounded terminal of input capacitor C1 is driven sharply positive by way of resistor R1 and transmits a pulse of the same polarity via diodes D1, D2 and the relatively small input resistor R4 to the base of transistor Q1. The transistor thereupon starts conducting so that the trickle current previously flowing through its primary winding N_p , in series with resistor R6 and winding N_f , progressively rises to drive the transistor into saturation. The e.m.f. developed at the same time across secondary winding N_f is of such polarity as to maintain the base potential positive, this positive potential being also communicated via circuit C2, R7 to the gate of controlled rectifier D4 whereby the previously charged condenser C4 discharges through transformer THT and fires the spark plug 10.

With saturation of transistor Q1 and/or transformer core 15, the bucking voltage in winding N_f decreases to apply a negative-going potential to the base of

transistor Q1. This reduces the current flow through primary N_p , and rapidly builds up a negative blocking potential in the transistor input until conduction ceases. At the same time the reversal of the polarity of the voltage developed across secondary winding N_L energizes the charging circuit for condenser C4 by way of diodes D3 and D5. With SCR D4 cut off by the negative potential on its gate electrode, the secondary current generated in winding N_L is prevented from circulating through the controlled rectifier. Meanwhile, the switch P has been reclosed by cam 12 so that the junction of resistor R1 and capacitor C1 is again grounded and the oscillator Ob constituted by transistor Q1 and associated elements is inhibited until the switch P reopens in the next cycle.

15 The provision of diode D5 enables the dissipation of residual energy electromagnetically stored in the primary of transformer THT after the electronic switch D4 has opened. On the other hand, the inclusion of resistor R7 in the control circuit of SCR D4 insures the presence of positive gate voltage throughout the discharge phase, thereby preventing a premature cutoff of the controlled rectifier which could otherwise occur, for example, prior to the firing of the spark plug 10 as a result of the counter-e.m.f. developed across the primary of transformer THT. This insures a complete discharge of the condenser C4 and prevents overcharges in subsequent cycles.

Resistor R3 and diode D2 protect the transistor Q1 and the controlled rectifier D4 from excessive negative 30 voltages during switchover between saturation and cutoff.

The energy stored in the core 15 of transformer Tr equals $\frac{1}{2}LI_m^2$ where L is the inductance of primary winding N_p and I_m is the peak current flowing through that winding during conduction of the transistor. This energy, a large part of which is transferred to the storage condenser C4, may range in magnitude between 50 and 75 mJoules with battery voltages ranging between 8 and 16 volts. With the same range of battery voltages V_b , the charging potential of storage condenser C4 may vary between 320 and 390 volts. The output voltage developed across the secondary winding of step-up transformer THT may reach 24 KV if the resistance of the spark gap of spark plug 10 is on the order of 1 $M\Omega$. With a 4-cycle engine operating at 7,000 RPM, the spark plug of each cylinder fires roughly at the rate of 60 cycles per second; the duration of the spark discharge is on the order of 200 μ sec, with a build-up period of about 20 μ sec for the breakdown voltage across the spark-plug electrodes. These parameters are comparable to those realized with considerably more complex conventional ignition circuits of the same general type.

50 I claim:

1. A system for intermittently igniting a spark-discharge device, comprising:
a source of direct current;
a blocking oscillator connected across said source, said oscillator including a transistor with an 60 emitter, a collector and a base, a coupling transformer having a primary winding inserted between said collector and a first terminal of said source,

said emitter being tied to a second terminal of said source, a capacitor in series with said base, switch means for alternately applying a blocking potential and an unblocking potential from said source to said capacitor, and a resistive connection between said base and the junction of said primary winding with said collector, said coupling transformer having a first secondary winding connected between said base and said emitter for intensifying said unblocking and blocking potentials upon incipient conduction and cutoff of said transistor;

an ignition circuit for said spark-discharge device including a condenser and an electronic switch in series;

a charging circuit including another secondary winding of said coupling transformer and diode means in series with said condenser; and

a control circuit for said electronic switch connected to said base for closing said electronic switch in the presence of said unblocking potential, thereby discharging said condenser through said ignition circuit, said other secondary winding being poled to recharge said condenser upon incipient cutoff of said transistor.

2. A system as defined in claim 1 wherein said electronic switch is a controlled rectifier with a gate electrode connected to said control circuit.

3. A system as defined in claim 1, further comprising a resistive voltage divider inserted between said capacitor and said base, said resistive connection being joined to said voltage divider at a first tap thereof relatively remote from said base, said control circuit being connected to said voltage divider at a second tap thereof relatively close to said base.

4. A system as defined in claim 3 wherein said control circuit includes a capacitance and a resistance in parallel.

5. A system as defined in claim 3 wherein said first secondary winding is connected between said emitter and said first tap.

6. A system as defined in claim 5, further comprising a first diode shunting said voltage divider between said capacitor and said first tap, and a second diode shunting said voltage divider between said first and second taps, said diodes being poled to pass said unblocking potential.

7. A system as defined in claim 1 wherein said transistor is provided with an integrating network connected between said base and said emitter.

8. A system as defined in claim 1, further comprising a leakage resistor connected between said capacitor and said first terminal, said switch means being operable to connect said second terminal to the junction of said leakage resistor with said capacitor for applying said blocking potential to the latter.

9. A system as defined in claim 1 wherein said ignition circuit includes a step-up transformer in series with said condenser and said electronic switch.

10. A system as defined in claim 1 wherein said device is a spark plug of an internal-combustion engine, said switch means comprising a cam driven by said engine.
